FLAG HOLDER

Adolf Liermann, Philadelphia, Pa.

Application February 23, 1942, Serial No. 431,981

4 Claims. (Cl. 248—39)

This invention relates to flag holders and has reference more particularly to flag holders of the type intended for the display of flags at windows.

My invention has for its main object the provision of a holder which will support a pair of flags at an inclination to each other, and which will at the same time define the letter V—which has recently been adopted as the symbol for "victory."

A further aim of my invention is to attain the foregoing desideratum in a flag holder which lends itself to production expeditiously from relatively thin sheet material such as stiff stout cardboard with incorporation of novel structural features whereby the holder is stiffened against flexure for capacity to respectively support the flags and resist easy bending, and whereby it may be attached to or held by the lower rail or bar of a window sash or be otherwise supported.

Other objects and attendant advantages will appear from the following detailed description of the attached drawing, wherein Fig. 1 is a fragmentary view in elevation of the out-door side of a window with my improved flag holder.

Fig. 2 is a fragmentary sectional view drawn to a larger scale and taken as indicated by the angled arrows II—II in Fig. 1.

Fig. 3 is a rear perspective view of the flag holder; and

Fig. 4 shows the stamping or blank from which the holder is formed.

From these illustrations it will be seen that my improved flag holder is fashioned from sheet material which may be of metal, stiff stout paper or light cardboard with an upper portion 10 having the configuration of the letter V and a central lower supporting portion 11 which is pendent from or connected at the vertex of the V which may be secured by means of thumb tacks, for example, to the lower rail R of a window sash S, or which may be held in place by engaging its lower edge between the lower rail of the sash and the face F of the shoulder of the window sill, as shown in Fig. 2. From Fig. 3 it will be noted that the holder is provided with flanges 12 along the outer sides of the bars 13 of the V and also with flanges 14 along the inner edges of these bars. The upper portions of the flanges 12 are detached from the bars 13 and bent laterally as shown at 15 in Fig. 3, and notched adjacent their ends as at 16 to engage over the inner flanges 14. The bent over portions 15 of the

outer flanges 12 are moreover provided with holes 17. The holder is formed along the tops of its bars 13 with laterally bent flanges 18 which have holes 19 aligned with the holes 17 in the direction of the bars 13 of the V for receiving the stems or rods 20 of the flags 21, the flags being thereby supported at an inclination to each other. Due to the flanged construction just described, the bars 13 of the V 10 are effectively reinforced against easy bending, the resistivity to distortion or bending being further enhanced through engagement of the flag rods with the crosswise portions 15 of the outside flanges and the top flanges 18 of the bars. The flag holder is formed in practice from a blank configured as shown in Fig. 4 by cutting or die stamping and by bending the flanges 12, 14 and 18 up all in the same direction at right angles to the main portion of the blank and by subsequently bending back the free portions 15 of the side flanges 12 and locking them with the inner flanges 14 of the bars as shown in Fig. 3.

Having thus described my invention, I claim:

1. A flag holder formed from relatively thin stiff sheet material with an upper portion having the configuration of the letter V; a lower supporting portion at the vertex of the V; and projections at the rear along the length of the bars of the V and apertured to receive the stems of a pair of flags.

2. A flag holder according to claim 1, in which the bars of the V are stiffened by lateral flanges along their opposite side edges.

3. A flag holder according to claim 1, in which the bars of the V are stiffened by lateral flanges along their opposite side edges; and in which the rearward projections are constituted respectively by inwardly turned portions of the outer stiffening flanges of the side bars and flanges along the top edges of said side bars.

4. A flag holder according to claim 1, in which the bars of the V are stiffened by lateral flanges along their opposite side edges; in which the rearward projections are constituted respectively by inwardly turned portions of the outer stiffening flanges of the side bars and flanges along the top edges of said side bars; and in which the laterally bent portions of the outer side flanges are notched to lock over the flanges along the inside edges of the V bars.

ADOLF LIERMANN.
